TILMAN WHITE, OF JERSEY CITY, NEW JERSEY, ASSIGNOR TO PERMEX CORPORATION OF AMERICA, A CORPORATION OF NEW JERSEY.

AUTOMATIC VALVE CONTROL.

Application filed June 5, 1924, Serial No. 718,165. Renewed April 29, 1926.

My invention relates to improvements in automatic valve control mechanism, and more particularly has reference to and is illustrated in the accompanying drawings 5 in its application to means in combination with a valve such as a gas valve for automatically operating the same and cutting off the supply of gas upon the happening of a predetermined event such as an undue 10 rise of temperature.

In said drawings, I have illustrated in Fig. 1 in side elevation a suitable form of valve and automatic control mechanism therefor, embodying an application of my 15 invention. Fig. 2 is a perspective detail of one of the operating parts. Fig. 3 is a similar view of another operating part; Fig. 4 is a front elevation of the device, the position of certain parts, after the valve has been 20 operated, being shown in dotted outline, and Fig. 5 is a detail partly in section illustrating the construction of the valve closure.

6 indicates a suitable form of box or outer casing having a suitable hook or ring at the 25 top such as 7 from which may be suspended a link or chain such as 8. 9 indicates a similar link suitably secured to the link 8 by suitable means such as solder or fusible material adapted to melt or fuse and allow 30 the links to separate where joined, as indicated at 10. The lower link preferably passes through a hook or hole such as 11 secured to or formed with a weighted member such as 12 which in turn is mounted 35 upon the shaft 13 and is free to rotate thereupon, said shaft at the right, looking at Fig. 1, being rectangular in cross-section upon which is mounted the weighted member or counterweight 14 of less weight than 40 the weighted member 12 and which is retained thereon by any suitable means such as the cotter pin 15. 16 indicates an offset or lug projecting laterally from the counterweight 14 in the path of movement of the 45 shank or stem 17 of the weighted member 12, so that when the weighted member 12 is released by the fusing and separating of the links 8, 9, the same in dropping brings the stem 17 across the path of the lug 16, 50 thereby throwing the counterweight 14 upwardly and leftwardly looking at Fig. 4 past its dead centre position until it drops in the position indicated in dotted outline by reference character 14'. This counter- 55 weight having a rectangular hole for pas-

sage over the rectangular end of the shaft 13 of course turns the shaft as the same is rotated leftwardly by the weight 12.

The shaft 13 is provided with another rectangular section long enough to receive 60 the carrier or arm 18 shown to better advantage in Fig. 3, and terminates at the left end in a reduced rounded portion which has its bearing in the casing of the valve as indicated at 19. This arm 18 is drilled 65 and tapped at 51 to provide engagement for the bolt 20 which is screwed upwardly there-through looking at Fig. 4 and is provided with a lock-nut 21 to secure it in proper position in the arm 18. The lower end of 70 the bolt 20 is provided with a suitable head 22 and the bolt having been first passed through the closure 23 of the valve, retains the same as shown, the hole through the closure 23 and through which the bolt passes 75 being slightly larger than the diameter of said bolt to allow for a little play. Said closure member 23 is also bored larger in the direction of the lower or rounded side thereof, and is provided with a threaded 80 plug 24, as shown. 25 indicates a suitable washer which may be introduced between the head 22 of the bolt and threaded plug 24 to allow a seating for said bolt, from all of which it will be seen that as the arm 18 85 moves downwardly anti-clockwise when the weight 12 is released, it carries with it the closure 23 which also shifts anti-clockwise until in the position shown in dotted outline as indicated at 23', thereby shutting off the 90 gas, water, or other medium to be controlled. Such medium enters leftwardly looking at Fig. 4 through the inlet 26 and passes through the valve, escaping by the outlet 27. The passage 28 through the valve 95 it will be observed is slightly tapered so as to provide a seating as indicated at 29 for the closure 23, said closure being adapted to readily find its seating by virtue of the play allowed for between the same and the 100 bolt 20.

In addition to being automatically operative, the valve is manually operative as follows:—Upon the lug or casting 30 of the valve a suitable strap or plate 31 is secured 105 in any suitable manner such as by the screws 32, and to the outer end of said plate 31 is secured a housing 33 as indicated by the screws 34. Within this housing is mounted a sheave or grooved pulley 35 upon which 110

one end of a rope or wire cable 36 is secured as indicated at 37, the same passing around in the groove of the sheave, the free end passing through the outlet 38 as shown in Fig. 4. As a further means of support for the case or frame 33 of the sheave, a yoke or U-shaped strap such as 39 is provided with a round hole as indicated at 40 for the passage of the shaft 13, the inner ends being secured by screws 41, 42 to the casing 33. The said sheave or grooved pulley is also provided with a projection or finger such as 43 which upon the rotation of the pulley moves in the path of the cut-away portion of the member 46, shown to advantage in Fig. 2. This member is so adjusted upon the rectangular portion of the shaft 13 that when the cable 36 is pulled and the projection 43 encounters the face 44 or 45 of the member 46, it rotates the shaft 13 the same as the counterweight 14 when the weight 12 is released, thereby throwing the valve manually in the same manner as if operated automatically. 47 indicates a suitable cap or closure adapted to be screwed down upon the valve casing 48 after the valve closure 23 and other parts have been suitably secured in place. 49 indicates a hollow thimble externally threaded as shown to engage interior threads in the casing 48 to provide bearing for the shaft 13 and is suitably screwed into position by the slot 50 during the assembly of the valve.

In the position shown in the drawings, the valve is adjusted for operating upon a horizontal or transverse conduit or piping, but of course it will be readily understood that by shifting the mounting of parts, such as the arm 18 and member 46, ninety degrees, the valve will operate upon a vertical line of pipe, and the same of course applies to the weights 12 and 14.

Of course it will be understood that various modifications may be made in the construction and arrangement of parts without departing from the spirit of the invention as claimed.

I claim:—

1. In a heat released device the combination with a movable valve member, and seat therefor, of a weight member normally tending in one position to hold said valve away from its seat, and heat released means for moving said weight member to another position to close said valve, said weight member in said second mentioned position acting to hold said valve closed against its seat.

2. In a heat released device of the class described, a weighted member adapted to be moved past a dead center position for operating a valve, said weighted member adapted to complete the operation of said valve after passing said dead center, and a movable weighted member forward of and operatively connected to the first mentioned

weighted member to operate the valve until the first mentioned weighted member becomes operative.

3. In a heat released device of the class described a weighted member adapted to be moved past a dead center position for operating a valve, said weighted member adapted to complete the operation of said valve after passing said dead center, and a movable weighted member forward of and operatively connected to the first mentioned weighted member to operate the valve until the first mentioned weighted member becomes operative, the second of said weighted members being of greater weight than the first mentioned. 75

4. In a heat released device the combination with a movable valve member and a seat therefor, of means comprising a weighted member normally holding said valve away from its seat, heat released means for actuating said holding means to cause it to close the valve, connecting means between said holding means and said heat released means permitting movement of the valve independently of the latter, and means for manually moving said valve. 85

5. In a device of the class described, an automatically and manually operative valve adapted to close in the direction of the flow of fluid and having a device comprising a weight adapted to be moved automatically or manually past a dead center position for automatically operating the valve. 95

6. In a heat released device of the class described the combination with a gas shut-off valve, of means normally holding said valve open and adapted for actuation to close said valve and hold it closed, heat released means for automatically actuating said closing means upon the occurrence of a predetermined temperature, and means operable at a distance for actuating said closing means to cause a closure of said valve. 100

7. In a heat released device of the class described the combination with a gas shut-off valve, of means normally holding said valve open and adapted for actuation to close said valve and hold it closed, heat released means for automatically actuating said closing means upon the occurrence of a predetermined temperature adjacent said valve, and means operable at a distance for actuating said closing means to cause a closure of said valve. 110

8. In a heat released device of the class described the combination with a gas shut-off valve, of means normally holding said valve open and adapted for actuation to close said valve and hold it closed, heat released means for automatically actuating said closing means upon the occurrence of a predetermined temperature adjacent said valve comprising a member adapted to store up kinetic energy and deliver said energy 120

125

130

to said closing means, and means operable at a distance for actuating said closing means to cause a closure of said valve.

9. In a heat released device of the class described the combination with a gas shut-off valve, of operating means therefor normally holding said valve open, and a separate heat released means normally out of operative engagement with said operating means and movable upon occurrence of a predetermined temperature to engage said operating means and actuate the same to cause a closure of said valve.

10. The combination with a shut-off valve, of operating means therefor normally tending to hold the valve open comprising a shaft operatively connected to said valve and a weight on said shaft, and means for actuating said operating means to close the valve comprising a releasably restrained weight mounted on said shaft and adapted when released to engage said first weight to move the latter to position to close the valve and hold it closed.

11. The combination with a movable valve member and a seat therefor, of means tending in one position to hold said valve away from its seat, and heat released means for moving said first mentioned means to position to close the valve and hold it closed.

12. The combination with a gas shut-off valve and a seat therefor, means normally tending to hold said valve open, and a heat released weight for moving the valve to closed position to be held in the latter position by said first mentioned means.

13. In a valve operating mechanism of the class described, a valve spindle, a weight normally supported at one side of the center of the spindle for holding the valve open, an-

other weight normally retained against gravity by a fusible link and adapted when said link is fused to throw said first mentioned weight over the center of said spindle, whereby said valve is closed and the first mentioned weight retains said valve in closed position.

14. In a valve operating mechanism of the class described, a valve spindle, a weight normally supported at one side of the center of the valve spindle for holding the valve open, another weight normally retained against gravity by a fusible link and adapted when said link is fused to throw said first mentioned weight over the center of the spindle, whereby said valve is closed and the first mentioned weight retains said valve in closed position, and a lever connected to said spindle adapted to be operated by the falling of said second mentioned weight.

15. In a valve operating mechanism of the class described, a valve spindle, a weight normally supported at one side of the center of the valve spindle for holding the valve open, another weight normally retained against gravity by a fusible link and adapted when said link fuses to throw said first mentioned weight over the center of the spindle, whereby said valve is closed and the first mentioned weight retains said valve in closed position, and a lever connected to said spindle adapted to be operated by the falling of said second mentioned weight, and in combination, a second lever, and manual means for operating the same, for operating said valve independently of the second mentioned weight.

In testimony whereof I hereunto affix my signature.

TILMAN WHITE.
